Primary Examiner — Ania Aman(74) *Attorney, Agent, or Firm* — The Dobrusin Law Firm, P.C.(57) **CLAIM**

The ornamental design for a snorkel system, as shown and described.

DESCRIPTION

FIG. 1 is a front perspective view of a snorkel system showing our new design.

FIG. 2 is a front elevation view of FIG. 1.

FIG. 3 is a left side elevation view of FIG. 1.

FIG. 4 is right side elevation view of FIG. 1.

FIG. 5 is a top plan view of FIG. 1.

FIG. 6 is a bottom plan view of FIG. 1; and,

FIG. 7 is a back elevation view of FIG. 1.

The broken lines are used to show unclaimed portions of the snorkel system and form no part of the claimed design.

1 Claim, 6 Drawing Sheets
